PUMP

Lawrence C. Dermond, Rochester, N.Y., assignor to General Motors Corporation, Detroit, Mich., a corporation of Delaware

Filed Sept. 29, 1958, Ser. No. 763,932

4 Claims. (Cl. 103—150)

The present invention relates to an improved type diaphragm actuated pump in which the movement of the diaphragm controls pump actuation. More specifically the present pump is of the type in which reciprocation of diaphragm means is adapted to draw liquid into and expel liquid from a chamber under the influence of a pneumatic force acting on the diaphragm means and which force is controlled by the position of such means.

While the subject pump is of general applicability, it is particularly effective when used as an automotive fuel pump on a vehicle having a convenient source of air pressure. In traditional pumps of the diaphragm type, it has been the practice to actuate the diaphragm through a cam and lever arrangement driven in accordance with engine speed. The present device represents an improvement over a mechanically driven type diaphragm pump in that all such mechanical actuating parts are eliminated and replaced with a simple air switch mechanism greatly reducing both the cost and size of such pump.

It is particularly an object of the present invention to provide a simple yet reliable air switch mechanism which will control the admission and exhaust of air into a diaphragm actuating chamber. The air switching mechanisms for the subject pump includes an overcenter type valve device which is actuated through an interconnection with the pump diaphragm so as to admit air pressure into the diaphragm chamber in one position and to exhaust such pressure therefrom in another position. This control of air pressure in combination with a diaphragm actuating spring combines to provide a simple but effective system for reciprocating the pump diaphragm.

Other objects and advantages of the present invention will be apparent from a perusal of the detailed description which follows.

In the drawings:

Figure 1 is a sectioned elevational view of the subject pump; and

Figure 2 is a plan view of the pump showing particularly the air switch mechanism.

Referring to Figure 1, a diaphragm type pump is shown generally at 10 and includes a first or fuel casing 12 having inlet and outlet passages 14 and 16. A second or air casing is shown at 18 and is adapted to be mounted on fuel casing 12 through an intermediate casing 20. A first or fuel diaphragm 22 is peripherally clamped between the fuel casing 12 and intermediate casing 20. A second or air diaphragm 24 is peripherally clamped between air casing 18 and intermediate casing 20.

In order to multiply the force available to pump fuel through casing 12, a differential area relationship is established between diaphragms 22 and 24. The differential area effect is achieved by forming the associated casings in such a way that the area of fuel diaphragm 22

is smaller than the area of air diaphragm 24. The desirability or need for this differential area effect is due to the fact that the air utilized for actuating diaphragm 24 is normally at a lower pressure value than is desired for pumping the fuel. Therefore, by the use of the differential area diaphragms, the fuel pumping pressure may be increased to its desired value. The chamber 26 defined by diaphragms 22 and 24 as well as casing 20 is vented to the atmosphere through a passage 28.

10 The fuel and air diaphragms are interconnected through a central stud 30 suitably secured to respective sets of reinforcing washers 32 and 34 whereby the diaphragms move in unison under the influence of the various actuating forces as will subsequently be considered.

15 The fuel casing 12 includes a chamber 36 which is communicated with the inlet and outlet passages 14 and 16 respectively through inlet and outlet valve devices 38 and 40. The inlet and outlet valve devices are of identical construction but are inverted with respect to each other so that when one is open the other will be closed and vice versa. While not shown in detail, valve devices 38 and 40 may include gravity or spring seating discs disposed in supporting cages such that the disc permits flow when moved in one direction and blocks such in the other direction. Inlet valve 38 is so arranged that upon the upward movement of diaphragm 22 fuel will be drawn into chamber 36. At the same time the outlet valve 40 will be closed. Downward movement of diaphragm 22 causes inlet valve 38 to close 20 and outlet valve 40 to open permitting fuel from chamber 36 to be expelled through fuel outlet passage 16.

To facilitate easy servicing of pump 10, the lower portion of fuel casing 12 is enclosed by a cover plate 42 removably secured to casing wall 44 through a stud 35 member 46. Casing wall 44 separates the inlet and outlet fuel passages 14 and 16.

A spring 50 is seated upon wall 44 and engages reinforcing washer 32 of diaphragm 22 urging the diaphragm assemblies in an upwardly or pump charging direction.

40 To move the diaphragm in a fuel discharging direction against the force of spring 50, an air valve controlling mechanism indicated generally at 52 is provided for controlling the flow of air into and out of air chamber 54 defined by casing 18 and diaphragm 24.

45 The air valve mechanism is disposed in a raised portion 56 of casing 18 and enclosed by a removable cover plate 58. The chamber 60 within which the valve mechanism is disposed is in open communication with diaphragm chamber 54. An air inlet passage 62 is formed in casing 18 and terminates at its inner end in an upstanding boss portion 64 within chamber 60. A similar passage 66 and boss 68 are formed in casing 56 in vertically spaced relation to inlet boss 64. Passage 66 communicates the chamber 60 to the atmosphere to exhaust any air 50 pressure within the chamber when such passage is open. It is to be noted that bosses 64 and 68 are laterally offset from each other.

To control the flow of air through the inlet and exhaust passages 62 and 66, an overcenter type valve mechanism 60 70 is provided. As best seen in Figure 2, valve 70 includes a generally flat or reed member 71 terminating at one end in a bifurcated portion 72. A spring member 74 is secured at one end to valve member 70 intermediate the legs of the bifurcated portion 72. The spring 65 is secured at its other end to casing 56 to urge the valve axially against a stop member 76 formed on casing 56.

70 Valve member 70 also includes a pair of axially spaced closure elements 78 and 80 adapted to respectively coact with inlet and outlet passage bosses 64 and 68. It is desirable to position valve member 70 vertically intermediate the air inlet and outlet bosses 64 and 68 so that

the point of pivotal contact between the bifurcated portion 72 of valve 70 and stop 76 is on a line vertically equidistant between bosses 64 and 68 to achieve an overcenter or toggle type actuation of member 70. In other words, if valve member 70 is moved downwardly causing the closure member 78 to seat against the air inlet boss 64, member 70 will pass overcenter. A component of spring force is thereby created which urges member 70 in a clockwise direction to retain the valve in this position until such time as it is moved overcenter in the opposite direction. In this latter instance, the other closure member 80 will seat against boss 68 closing the exhaust passage 66 with the spring 74 again retaining the valve in this position due to its overcenter action as noted.

It is apparent that it is necessary only one of the passages 62 or 66 be opened at the same time the other is closed. Therefore, valve member 70 has only two positions, e.g. a lower position in which closure member 78 blocks the air inlet passage 62 under which circumstance exhaust passage 66 is open and an upper position closing exhaust passage 66 and opening inlet passage 62.

Valve member 70 is shifted between its two positions by an upstanding actuating arm 82 fixed at one end to diaphragm stud 30 and terminating at its other end in a horizontally extending bifurcated portion 84. The bifurcated portion of arm 82 includes the fingers 86 and 88 adapted to coact with the free end of valve member 70.

With the parts in the position shown, the air inlet boss 64 is covered by closure member 78 and the exhaust boss 68 is uncovered whereby chambers 54 and 60 are maintained at substantially atmospheric pressure. Under this condition, spring 50 will move the diaphragm assembly 22-24-30 upwardly until such time as the lower finger 88 of arm 82 engages valve member 70 moving the same in an upwardly direction until spring 74 passes overcenter. At this time exhaust boss 68 will be closed and air inlet boss 64 opened to admit air into chamber 60. As the air pressure in chambers 60 and 54 builds up, diaphragm 24 will be moved downwardly causing diaphragm 22 to pump fuel from chamber 36. Downward movement of the diaphragms continues until such time as upper finger 86 of arm 82 engages valve member 70 to again shift the member to its lower position to cut off the supply of air and exhaust the pressure in chambers 54 and 60 returning the diaphragms to their upper or charging positions.

Thus the actuation of air valve mechanism 52 is controlled by the movement of the diaphragm assembly and the pumping cycle will continue so long as the pressure in chamber 54 is sufficient to overcome the back pressure of the fuel in outlet passage 16. The stroke of pump 10 is determined by the space between fingers 86 and 88 of arm 82, accordingly, the stroke may be varied by varying such distance.

I claim:

1. A pump comprising three stacked casing members, first and second diaphragm means respectively peripherally clamped between adjacent of said three casing members, the first casing member including a first set of fluid inlet and outlet passages, a fluid chamber defined by said first diaphragm means and said first casing member, an inlet valve disposed intermediate said chamber and said inlet passage, an outlet valve disposed between said chamber and said outlet passage, movement of said diaphragm means in one direction being adapted to draw fluid into said chamber through said inlet valve, movement of said diaphragm means in the opposite direction being adapted to expel fluid from said chamber through said outlet valve, a second fluid chamber formed by said second diaphragm means and the second casing member, a second set of fluid inlet and outlet passages formed in said second casing member, an overcenter valve member mounted in said second casing and mov-

able to a first position opening said inlet passage and closing said outlet passage, said valve member movable to a second position opening said outlet passage and closing said inlet passage, means associated with said 5 first and second diaphragm means for positioning said overcenter valve member in either said first or second positions, and resilient means for moving said first and second diaphragm means in a direction to position said overcenter valve member in said first position, said second 10 set of inlet and outlet passages including a pair of spaced and oppositely facing boss members, said second set of passages being formed in said boss members so that they open toward but are spaced from each other, and further in which said overcenter valve member includes a flat plate element being disposed intermediate said boss members and including closure portions adapted to respectively seat against and block flow through either the respective second inlet or the second outlet passages, said valve plate element being pivotally 15 supported on said second casing member, spring means connected at one end to said plate element and at the other end to said casing in coaxial relation to the valve element, said spring means urging said element into engagement with said second casing member, said diaphragm associated means being adapted to engage with and urge said valve element into either of said first or second positions, said spring means being adapted to retain said valve element in either said first or second position until such time as the diaphragm associated 20 means shifts the valve element to the other position.

2. A pump comprising first and second casings, a casing intermediate said first and second casings, a first flexible diaphragm means peripherally clamped between said first and intermediate casings, said first casing including 25 fluid inlet and outlet passages, a chamber formed by said first diaphragm means and said first casing, a second diaphragm means peripherally clamped between said second casing and said intermediate casing, an air chamber formed by said second diaphragm means and said second casing, a stud member interconnecting the diaphragms in spaced relation, an inlet valve disposed in said first casing intermediate said chamber and said inlet passage, an outlet valve formed in said first casing intermediate said chamber and said outlet passage, air inlet and outlet 30 passages communicating with said air chamber, valve means mounted in said second casing intermediate said air inlet and outlet passages, said valve means being movable to a first position uncovering said air inlet passage and covering said air outlet passage and a second position covering said inlet passage and uncovering said outlet passage, an arm fixed to said stud member and operatively connected to said valve means to shift the latter between its first and second positions, said air inlet and outlet passages including a pair of spaced and oppositely 35 facing boss members, said passages being formed in said boss members so that they open toward but are spaced from each other, said valve means including a flat plate element being disposed intermediate said boss members and including closure portions adapted to respectively seat against and block flow through either the air inlet or air outlet passage, said valve element being pivotally supported on said second casing member, spring means connected at one end to said element and at the other end to said casing in coaxial relation to the valve element, said 40 spring means urging said plate element into engagement with said casing, said arm including a bifurcated end portion having first and second fingers adapted respectively to engage with and urge said valve element into said first and second positions, said spring means being adapted to retain said valve element in either said first or second position until such time as the arm shifts the valve element to the other position.

3. A pump as set forth in claim 2 in which the first and second fingers of said arm are spaced from each

other permitting relative movement between said valve element and said arm.

4. A pump as set forth in claim 2 in which the pivotal support of the valve element on the second casing member is disposed on a line equidistant between said boss members, said spring means being axially aligned with the valve element and exerting no rotating moment on said element when the latter is aligned with said equidistant line.
